ROSE BUD E. KALLAM.
COMBINED RIBBON HOLDER AND MEASURING DEVICE.
APPLICATION FILED OCT. 4, 1912.

1,082,337.

Patented Dec. 23, 1913.

UNITED STATES PATENT OFFICE.

ROSE BUD ELLEN KALLAM, OF RURAL HALL, NORTH CAROLINA.

COMBINED RIBBON HOLDER AND MEASURING DEVICE.

1,082,837.

Specification of Letters Patent.

Patented Dec. 23, 1913.

Application filed October 4, 1912 Serial No. 723,966.

To all whom it may concern:

Be it known that I, ROSE BUD ELLEN KALLAM, residing at Rural Hall, in the county of Forsyth and State of North Carolina, have invented certain new and useful Improvements in Combined Ribbon Holders and Measuring Devices, of which the following is a specification.

My invention has for its object to provide 10 a simple, inexpensive and conveniently manipulated means for measuring ribbon, belting, and like fabrics held on spools as the same is unwound or drawn off the spool and in such a manner that the person selling the 15 ribbon, or other fabric, or taking stock, can tell at a glance how much is still on the roll and can accurately unwind from the roll the exact amount or length of the ribbon, belting, etc., desired by the purchaser.

My invention also seeks to provide a device or means of the general character described, in which the component parts are especially designed for holding the material wrapped on the spool in a neat and compact 25 shape, and which also includes gripper members whereby the spool containing the ribbon can be readily held in one hand as the desired amount of the ribbon or band is pulled off or unwound with the other hand.

With other objects in view that will hereinafter appear, my invention comprises the peculiar construction and novel arrangement of parts hereinafter fully explained, specifically pointed out in the appended 35 claims, and illustrated in the accompanying drawing, in which:

Figure 1, is a perspective view of my improved device, the same being shown as in use. Fig. 2, is a transverse section thereof taken on the line 2—2 on Fig. 1, the gripper holding member being omitted. Fig. 3, is a detail perspective view of a portion of the measuring tape, the ribbon and winding strip. Fig. 4, is a detail perspective view 5 of the spool axle, the clamp or cross bar and the tension springs that coöperate therewith. Fig. 5, is a detail view of the spool holder or gripper. Fig. 6, is a detail modified form of my invention.

In carrying out my invention, I provide a body or drum 1, formed of thin cardboard, or other suitable cheap material, the ends of which are centrally reinforced and formed with apertures 10.

2, designates a tubular axle formed of light (preferably tin) material, having a

length somewhat greater than the drum, whereby the opposite ends project beyond the sides of the drum, the said ends terminating in non-circular socket-like members 21, the reason for which will be presently explained.

The bolt of cloth, ribbon, or other fabric 4, is wound upon the drum, the ribbon or other fabric to be sold, being preferably narrower than the separating paper strip 3 with which the ribbon is usually wound, the said strip being wider than the ribbon to protect the edges of the said ribbon or fabric 4.

5 designates a mensurator which in the complete arrangement of my device is in the nature of an ordinary tapemeasure, it being, in my case, of a very thin cheap cloth, since no strength is required of it 75 and whereby that part used for measuring the sold, torn, or cut off ribbon sections may be readily torn or cut off with the ribbon. The strip or tape 5 has measuring scales on both faces, the inches being preferably stepped 80 off on the upper side and the yards on the under side thereof. The measuring tape 5 in practice, is made up in, say ten, fifteen yards, more or less, it being in each instance as long as the material to be measured, and it is wound up with the winding paper and the ribbon or other fabric to be sold.

For holding the ribbon and other windings in proper position on the drum and to 90 provide a measuring and severing point, a thin spring steel plate or bar 6 is transversely mounted on the windings that is normally held under spring tension on the said windings by two coiled springs 7—7 95 detachably connectible to the ends 60 of the bar, the latter extending laterally of the spool windings. The outer ends of the springs terminate, in hooks 70 for interlocking with the apertures 61, in the plate 100 ends 60, and the inner ends are connected to the extended ends of the tubular axle 2, as shown.

For conveniently holding the spool while winding or reeling off the windings, I have 105 provided what I term a "gripper" for holding the axle and the cross plate 6 stationary while winding up or unwinding the ribbon. The gripper 8 comprises a bow shaped body 8 the opposite ends of which are in the nature of spring arms 80 and each of the said arms has a projection or point 81 shaped to

snugly fit into and interlock with the hollow non-circular ends of the tubular axle 2, as is clearly shown in Figs. 1 and 2 of the drawing.

5 By reason of the peculiar construction and arrangement of the parts as before described and shown in the drawings, the salesman can readily pick up and hold any desired one of the drums that hold the ribbon or other fabric, and from which it is desired to remove a section, by closing the spring arms 80 over the ends of the axle 2, the points 81 seating in the axle sockets and thereby holding the axle with the cross plate 6 stationary, as the drum or spool is turned on the axle during the operation of pulling off the desired portion of the ribbon, the portion desired being readily measured, since the measuring tape is pulled out with 20 the ribbon until the exact amount desired is indicated. For example, if three yards is wanted—the ribbon and the measuring tape is pulled out until the three yards indicator comes in line with the front edge 25 of the cross bar 6, when the drawn off ribbon end and the tape can be readily cut or torn off from the remaining bulk of the ribbon.

While I have specially shown and described my invention as applicable for measuring ribbon or fabrics sold from the bolt or bulk, it is obvious the same may be readily adapted for measuring off any material that will run on spools, such as belting, elastic, lace, etc.

When used for selling small sized ribbons or the like the gripper need not be used, since in that case, the cross bar 6, is made relatively a little heavy, and its ends turned up to form finger holds 62 (see Fig. 6); it being apparent that by gripping the ends 62 of the bar 6, the said bar and the axle can be held stationary, as the material is pulled off the drum or spool.

45 While I prefer to use a gripper on certain large size spools, as indicated in Fig. 1, it is obvious that the finger holds 62 can be used successfully on all sizes of the device,

and the "gripper" need not necessarily be used at all.

What I claim is:

1. A device of the character described, comprising a drum adapted for receiving the fabric windings, and including a tape measure, a hollow axle for the drum whose opposite ends project beyond the drum and terminate in non-circular sockets, a hanger for the axle including a cross bar that passes over the windings on the drum, tension springs that connect the ends of the cross bar with the projected ends of the axle, and a hand held gripper including flexible side arms having members for engaging and interlocking with the non-circular sockets of the axle.

2. A device of the character described, comprising a rotatable drum on which the fabric is adapted to be wound, an axle passing through said drum and projecting beyond the same, a hanger bar for engaging the windings and extending across the outside of the drum parallel to the axis, said hanger bar including projecting portions, and coil springs at each side of the drum each having one end connected to said axle projections and their other ends connected to said bar, substantially as shown and described.

3. A device of the character described, comprising a rotatable drum on which the fabric is adapted to be wound, an axle passing through said drum and projecting beyond the same, a hanger bar for engaging the windings and extending across the outside of the drum parallel to the axis, said hanger bar including projecting portions, and coil springs at each side of the drum each having one end connected to said axle projections and their other ends connected to said bar, said bar having its ends offset to cause said projections to overhang the material that is wound on the drum.

ROSE BUD ELLEN KALLAM.
